MOTOR CONTROL PRIOR TO DYNAMIC BRAKING

George R. Purifoy, Pittsburgh, Pa., assignor to
Westinghouse Electric Corporation, East Pittsburgh, Pa., a corporation of Pennsylvania

Application January 27, 1953, Serial No. 333,546

3 Claims. (Cl. 318—63)

1

My invention relates to direct-current electrically propelled railway-vehicles, and it has particular relation to electrical control-systems thereof, in which provision is made for dynamic braking. The principal object of my invention is to provide a new means or instrumentality for reducing the high buildup-rate and overshooting of the motor-current and the motor-voltage when the dynamic-braking circuits are established while the motors are being operated at high speeds. Excessive motor-current and excessive motor-voltage result not only in a rough brake-application, but also in motor-flashing. My invention is an improvement over the control-equipment which is shown in a companion application of William L. Barclay, Jr., and myself, Serial No. 295,794, filed June 26, 1952, in which other means were provided for the purpose of mitigating overshooting when dynamic braking is applied.

I have provided an auxiliary switching-segment or segments on the field-controller, for taking care of an objectionable condition which sometimes occurs when the motorman elects to operate the car or train, for a while, on either the switching position or the series running position of the master controller, with the train running at speeds much higher than the normal switching-speeds or the normal series-running speeds, and subsequently going into dynamic brake from either said switching position or said series running position.

With the foregoing and other objects in view, my invention consists in the circuits, systems, apparatus, combinations, parts, and methods of design and operation, hereinafter described, and illustrated in the accompanying drawing, the single figure of which is a simplified circuit-diagram of the parts of one car, which are necessary to illustrate my present invention, omitting many parts which are known to be needed in a successful railway-control equipment of the type to which my invention is applied, but which are not necessary to be discussed in setting forth the nature and operation of my present improvement.

The drawing represents some of the equipment which is carried by a single electrically propelled railway-car embodying my invention. The principal novel feature, as shown in the illustrated form of embodiment of my invention, relates to the provision of contact-segments 220 and 253 on the field-controller FC, in addition to the contact-segment 305 which is shown in said companion-application.

Direct-current power is supplied to the car 55 cuits wherein the motor-armature or armatures

2

from a third rail 195, or a trolley wire, which is engaged by a third-rail shoe 196, or a trolley pole, pantograph, or other current-collecting equipment, carried by the car. The third-rail shoe 196 energizes a line 197 which constitutes a supply-circuit for the car. The traction-motors for the car are series motors, which are indicated, by way of showing a simple example in the drawing, as comprising two motor-armatures A1 and A2, each being associated with its own series field winding SF1 and SF2, respectively, the ordinary reversing-switches being omitted for the sake of simplicity. Two series-motor means, or circuits, are shown. The first series-motor means comprises, in series, an armature-terminal AT1, a motor-armature or armatures A1, an intermediate connection-point AX1, a series field winding or windings SF1, for supplying the field-excitation for said armature or armatures, and a field-terminal FT1. The corresponding parts for the second series-motor means are indicated at AT2, A2, AX2, SF2, and FT.

A series-parallel motor-control arrangement is shown in the drawing, in which a line-switch or relay LS1 and a ground-switch G1 are used as power-switch means for establishing a power-circuit for energizing the motors, by connecting the first armature-terminal AT1 to the supply-circuit 197, and connecting the second armature-terminal AT2 to ground. For completing the series-circuit connections, a switch JR is closed in addition to the power-switches LS1 and G1. For parallel-motor operation, two switches M and G are closed in addition to the power-switches LS1 and G1. The parallel-motor switch M provides a circuit-connection between the armature-terminal AT1 of one series-motor means and the field-terminal FT of the other series-motor means; while the other parallel-motor switch G provides a circuit-connection between the other armature-terminal AT2 and the other field-terminal FT1. During an intermediate transition-period, a switch J is closed. These motor-controlling connections are all in accordance with a well-known switching-system.

Dynamic-braking circuits are established by opening the two power-switches LS1 and G1 and closing a braking-switch B1 in addition to the two parallel-connection switches M and G, also in accordance with a well-known system or arrangement. The braking-switch B1 provides a common dynamic-braking circuit-connection 198 between the respective intermediate connection-points AX1 and AX2 of the two series-motor means, thus providing two dynamic-braking cir-

of each of said series-motor means are loaded by the field winding or windings of the other one of said series-motor means, respectively.

A progressively operating acceleration-controlling means is provided, in any suitable manner, including a first-operating voltage-controlling means for controlling the voltage which is effective on the motor-armatures A1 and A2. In the illustrated form of embodiment, this voltage-controlling means comprises a suitable number of series-connected accelerating resistances, as indicated at R1, R2, R3 and R4. The resistance R1 is disposed between the supply-line 197 and the first armature terminal AT1, and is shorted out by means of a second line-switch LS2. The resistance R2 is in series with the first field-terminal FT1, and is progressively shorted out by means of switch-contacts S1, S3 and S9. The resistance R3 is in series with the second field-terminal FT, and is progressively shorted out by switch-contacts S2, S4 and S10. The resistance R4 is in the series-motor connection which is made by the switch JR, and this resistance is finally shorted out by the transition-switch J, for obtaining the full-series power-circuit connection of the motors.

During parallel motor operation, the switch-contacts S3, S4 and S9, S10 are successively or progressively closed, during the acceleration of the motor, and after all of the accelerating-resistances R2 and R3 have been cut out, the acceleration-controlling means of my control-apparatus includes a finally-operating field-controlling means for progressively reducing the field-strengths of the motors, to provide short-field operating-conditions.

In accordance with a usual arrangement, the motor-fields are reduced by equipping each of the series field windings SF1 and SF2 with a field-shunt, comprising an inductive reactor X1 or X2, as the case may be, and a variable resistor RS1 or RS2, respectively. The field-shunts X1—RS1 and X2—RS2 are field connected in parallel relation to their respective field-windings SF1 and SF2, by means of contact-terminals 11 and 12, respectively, of a progressively or sequentially operating field-controlling means, which is herein illustrated as an electrically operated drum-type field-controller FC. After the respective field-shunts have been connected into operation, the field-shunt resistances RS1 and RS2 are then progressively shorted out by successive controller-points 13, 15, 17 and 19, for RS1, and 16, 18 and 20, for RS2, as the field-controller FC is moved from its initial full-field position FF, through its intermediate positions F1, F2, F3 and F4 to its short-field position SF, at which point the field-winding currents are reduced to about fifty per cent of their unshunted values.

During dynamic braking, the two motors are connected by the common dynamic-braking circuit-connection 198, which contains the braking-switch B1 and a braking-resistance R5. This resistance R5 is used, in addition to the previously mentioned accelerating-resistances R2 and R3, in establishing the complete dynamic-braking circuit. The braking-resistance R5 is progressively shorted out by means of braking-switches B2, B5 and B6, during dynamic-braking operations, after which the acceleration resistances R2 and R3, or portions thereof, are progressively shorted out, as by the switch-contacts S3, S4, and S9, S10. (The switch contacts S1 and S2 are

permanently closed during the dynamic-braking operations, in the illustrated system.)

The progressive operation of the various resistance-shorting switches, during both motoring operation and dynamic braking, is under the automatic control of a suitable limit-relay or relays, which are energized to be responsive to conditions which accompany excessive torque in the motors. Such a limit-relay is illustrated in the form of a current-relay CR, having an actuating-coil CR which is connected in series-circuit relation between the connection-point AX2 and the armature A2. This current-relay CR also has a back-contact 199 (also marked CR), which is normally closed, that is, which is closed in the non-actuated or low-current position of the relay.

The current-relay CR is also provided with certain recalibrating-means. In accordance with previous practice, this relay is provided with a cumulatively operating rate-coil RC, which is energized through a weight-responsive rheostat 200, during accelerating operations, and which is energized through a braking-responsive rheostat 201 during dynamic-braking conditions. The weight-responsive rheostat 200 is automatically adjusted according to the variable weight or live load carried by the car, so that the rate-coil RC is the most strongly excited during light-load conditions, thus reducing the minimum-current setting at which the limit-relay CR picks up and opens its back-contact 199. The braking-responsive rheostat 201 is automatically changed in response to the position of a brake-handle 202, which will be subsequently described, so that the rate-coil RC has its maximum excitation when a low braking-rate is called for, thus providing a low minimum-current setting at which the limit-relay CR picks up and opens its back contact 199, and also providing limit-relay calibration which is different from braking and power-operating conditions.

All of the electrically controlled relays and switches which are shown in the drawing are diagrammatically indicated as having vertical switch-stems (indicated by dotted lines), which are biased by gravity toward their lowermost positions, and all of these switches and relays are shown in their deenergized or non-actuated positions. All of the relays and switches are electrically controlled, and they are illustrated as being electrically or magnetically operated, by means of an appropriately numbered or lettered coil or solenoid, represented by a circle, acting magnetically to lift an armature which is represented diagrammatically by a smaller circle inside of the coil-circle. In general, the same switch-designation is applied to any particular switch, its coil, and its contacts, by way of identification of the parts belonging to a given switch or relay.

The various electrical control-circuits for a train are under the control of a number of train-line wires, which extend from car to car, throughout the entire length of the train (not shown). In the simplified circuit-diagram of the drawing, eight of these train-line wires are used, being given their usual designations, namely (+), 3, 4, 5, 6, 7, 12' and GS.

Energy for the various relay-circuits or switch-circuits is provided by means of a battery B on each car. The negative terminal (—) of each battery is permanently grounded, while the positive terminal of each battery is connected,

through a switch 203, to the positive train-line wire (+).

Each end of each car is provided with a motor-man's master controller MC, only one of which is indicated in the drawing. The illustrated master controller MC is indicated as being an accelerating-controller having an off-position and three on-positions 1, 2 and 3. In each of the three on-positions of the master-controller, MC, the positive control-wire (+) is connected to the train-line wires 12', GS and 6. The train-line wire 12' is the energizing-wire for the operating-coil LS1 of the line-switch LS1; while the train-line wire GS is the energizing-wire for the operating coil G1 of the ground-switch G1, as will be subsequently described.

In the second and third on-positions of the accelerating-drum of the master controller MC, the train-line wire 4 is energized from the positive bus (+); while in the third on-position of this controller, the train-line wire 7 is energized from the positive bus (+).

In the off-position of the accelerating drum or master controller MC, a connection is made from the positive control-wire (+) to the train-line wire 3. In the master controller MC, in accordance with a known practice, there is an overlap between the off-position contact which energizes this conductor 3, and the on-position contacts which energize the conductors 12' and GS, so that, during the notching-off of the master-controller MC, the contact at 3 is made before the contacts at 12' and GS are broken. This overlapping construction is particularly necessary in properly controlling a braking-operation protective-relay BP, which will be subsequently described, and which also constitutes the subject matter of a Riley Patent 2,597,183, May 20, 1952.

The first on-position of the accelerating-controller MC, in Fig. 1, is a switching position, in which the control-wires 12', GS, and 6 are all energized. The control-wire 12' energizes a control-circuit wire 10, through interlocks which are provided, by the braking-switches B1 and B5, in the form of back-contacts 204 and 205, respectively; and the control-circuit wire 10 is used to energize the operating-coil LS1 of the line-switch LS1.

In accordance with a usual practice, the exciting-circuit for the line-switch operating-coil LS1 also contains a make-contact 206 of a line-relay LR, which is a voltage-responsive relay which drops out upon a voltage-failure of the supply-line 197. This line-relay LR is shown as an undervoltage relay which has an operating-coil LR which is connected between the supply-line 197 and ground, through a back-contact 207 of the line-switch LS2, said back-contact 207 being paralleled by a make-contact 208 of the line-relay LR.

As set forth in an application of R. E. Burkhart and myself, Serial No. 269,752, filed February 4, 1952, the control-wire 10 energizes a control-wire 120 through a back-contact 209 of the line-relay LR. This line-relay back-contact 209 thus closes in the event of a power-line voltage-failure, which might result from either a third-rail gap or from any other cause; and if the master-controller MC is, at the time, on any on-position, the conductors 12' and 10 will be energized, and hence the line-relay back-contact 209 will energize the control-wire 120, which I use as an auxiliary holding-circuit for the protective relay or

brake-power relay BP, which I will subsequently described in more detail.

The train-line wire GS energizes the operating-coil G1 of the ground-switch G1, through interlocks which are provided by back-contacts 210, 211 and 212, which are carried by the braking-switches B1 and B5, and by the parallel-operation switch G, respectively. The back-contact 212 is paralleled by a make-contact 214 of the ground-switch G1.

The train-line wire 6 is connected, through an LS1 make-contact 215, to a relay-circuit 60, which is connected, through a G1 make-contact 216, to a circuit 62 which constitutes a hold-circuit for the switch-progression for the accelerating-resistance short-circuiting switches S1 to S10 and J. This hold-circuit 62 is used to energize the operating coil JR of the series-motor-circuit switch JR, through interlocks on the switches J and G, in the form of back-contacts 217 and 218, respectively.

According to my present invention, I also include, in the energizing-circuit of the JR-coil, a field-controller contact-segment 220, which is closed in the initial, full-field position FF of the field-controller FC, but which is opened when the field-controller is moved to its short-field position SF; or say when the field-controller is moved from its second on-position F2 to its third on-position F3. As shown, the new field-controller contact-segment 220 is included in a circuit which extends between the hold-circuit 62 and a control-circuit 63 which in turn energizes the operating coil JR of the series-motor-circuit switch JR through the interlocks 217 and 218. The purpose of this contact-segment 220 will be subsequently described.

The said hold-circuit 62 is also used to directly energize the close-coil or actuating-coil BP-Close of the braking-operation protective-relay BP.

The result of the master-control energization in the No. 1 on-position of the master-controller MC, is thus to close the main-circuit or power-circuit contacts of the traction-motor switches LS1, G1 and JR, thereby completing a series-connection motor-circuit for causing a slow movement of the train, for so-called "switching" purposes, with all of the accelerating-resistances in series with the motors. This circuit can be traced from the supply-circuit 197, through the main LS1 contact, the resistor R1, the armature A1, the series field SF1, the resistance R2, the resistance R4, the main JR contact, the resistance R3, the series field SF2, the current-relay coil CR, the motor armature A2, and the main G1 contact, to ground.

At the same time, the energization of the braking-operation protective-relay BP paves the way for the subsequent energization of the dynamic-braking circuits of the motors, and also for the automatic progression-control, under the control of the limit-relay or current-relay CR, both for the motoring progression during acceleration, and for the dynamic-braking progression during an application of the brake-lever 202, as will be subsequently described.

The hold-circuit 62, which is energized in the No. 1 on-position of the master-controller, is also connected, through an LS1 make-contact 222, to a hold-circuit 67, which is used in the subsequent progression-control.

The No. 2 position of the accelerating-controller MC is the first of two running-positions 2 and 3. It initiates the accelerating progression of the series-motor connections, by energizing the

train-line wire 4, which is connected, through an LS1 make-contact 224, to a conductor 40. The conductor 40 is connected, through an LS2 back-contact 225, to a conductor 42, which energizes the operating-coil LS2 of the second line-switch LS2, which acts as the first acceleration-progression switch, by short-circuiting the first accelerating-resistor R4. This LS2 switch has a make-contact 227 which picks up and serves as a holding-circuit contact between the circuits 60 and 42.

If there were any doubt about the adequate speed of closure of the series-motor-connection switch JR, the energizing-circuit for the first resistance-shorting switch LS2 could have included a JR-interlock (not shown in my drawing), to make sure that the JR-switch was closed, before the LS2-switch is energized, thus avoiding the possibility of skipping a resistance-reducing step because of the slowness of the JR-switch, as shown, for example, in the companion-application of Barclay and myself. In my present control-system, as will be more fully described, I provide a progression-system wherein the parallel-motor connection is sometimes made without progressing through the resistance-reducing sequence of the series-motor connection, but I want the LS2-switch to be closed, and hence I find it more convenient to make sure that the JR-switch is faster than the first resistance-shunting switch LS2, thereby avoiding the necessity for a JR-interlock in the energizing-circuit for the resistance-shorting switch LS2.

This second line-switch LS2, which serves as the first resistance-shorting switch, also has a make-contact 228 which connects the circuit 40 to a circuit 45. The circuit 45 is connected, through the CR limit-relay back-contact 199, and through a BP make-contact 230, to a circuit 46, which constitutes the main limit-relay progression-circuit of the control-equipment. This limit-relay progression-circuit 46 is thus not only under the control of the limit-relay or current-relay CR, which is responsive to excessive motor-currents, but it is also under the control of the braking-operation protective-relay BP, which must be closed (with the protective relay in its actuated position), before there can be any progression during either the motoring operation or the braking operation.

This limit-relay progression-circuit 46 is connected, through an LS1 make-contact 231, to a progression-wire 47, which is connected through an LS2 make-contact 232 to a control-wire 50. The control-wire 50 energizes the operating-coil 1-2 of a second resistor-shorting progression-switch 1-2, which carries the two main contacts S1 and S2, this energization being effected through a back-contact 233 of this same switch 1-2. Thus, this energizing-circuit from the conductor 50 includes the switch-out interlock 233, a conductor 51, and the coil 1-2. This second progression-switch 1-2 picks up and closes a holding-circuit make-contact 234, which energizes the circuit 51 from the hold-circuit 67.

The actuation of the second resistance-shorting switch 1-2 also closes a make-contact 235, which energizes a circuit 53 from the progression-circuit 47, through a back-contact 236 of a third resistance-shorting switch 3-4, which is the switch which carries the main switching-contacts S3 and S4. The energizing-circuit for this switch extends from the conductor 53, through the operating-coil 3-4 and a back-contact 237 of a fourth resistance-shorting switch 9-10, thence through a control-circuit conduc-

tor 109, and a J-switch back-contact 238, to the grounded negative battery-terminal (-). The actuation of the third resistance-shorting switch 3-4 closes a make-contact 239 which establishes a holding-circuit for the conductor 53 from the hold-wire 67.

The actuation of the third progression-switch 3-4 also closes a make-contact 241, which completes a circuit from the progression-wire 47 to a conductor 59, which energizes the actuating coil 9-10 of the fourth resistance-shorting switch 9-10, which carries the main switch-contacts S9 and S10, the negative terminal of said coil 9-10 being connected to the previously described wire 109. The actuation of this fourth switch 9-10 also closes a make-contact 242 which establishes a holding-circuit for the conductor 59 from the hold-wire 67.

The actuation of the fourth resistance-shorting switch 9-10 also closes a make-contact 243, which is connected between the progression-wire 47 and a circuit 65, through a back-contact 244 of the third resistance-shorting switch 3-4. This circuit 65 energizes the operating-coil J of the transition-switch J, through a G-switch back-contact 245. The transition-switch J then closes its main or power-circuit contact J, which constitutes the last step in series motor-connection for the traction-motors, cutting out the last accelerating-resistance R4. This transition-switch J has a make-contact 247 which establishes a holding-circuit from the conductor 65 back to the hold-line 62. The previously described J-switch back-contacts 217 and 238 are opened, upon the energization of the transition-switch J, thus dropping out the initial series-connection switch JR, and the third and fourth accelerating-switches 3-4 and 9-10.

The next step in the acceleration of the traction-motors is accomplished by a movement of the master-controller MC to its No. 3 position, which is a parallel-motor running-position. This position 3 of the master-controller energizes the train-line wire 7, which is connected, through a back-contact 249 of the fourth accelerating or resistance-shorting switch 9-10, and a make-contact 250 of the transition-switch J, so as to energize a control-circuit 31, which is in turn connected, through a JR back-contact 251, to a parallel-connection control-circuit 66 which energizes the operating-coils M and G of the parallel-motor-connection switches M and G. These switches M and G thereupon connect the traction-motors in parallel, between the supply-circuit 197 and ground, with only the first two of the resistance-shorting switches energized, in the illustrated form of embodiment of my invention—namely the second line-switch (or first progression-switch) LS2, and the second progression-switch 1-2 which carries the main switching-contacts S1 and S2. The energization of the parallel-connection switch G opens the previously described back-contact 246, which drops out the transition-switch J. The energization of the parallel-connection switch M closes a make-contact 252, which establishes a holding-circuit for the conductor 66 from the line 60.

According to my present invention, in addition to the interlock 252 of the parallel-connection switch M, I also provide a new field-controller contact-segment 253, connected in parallel to said M-switch interlock 252. This new contact-segment 253 thus connects the relay-circuit 60 to the parallel-connection circuit 66. Said contact-segment is closed whenever the accelera-

tion-progression of the traction-motor control has advanced far enough (as will be subsequently described) to move the field-controller to any position close to its short-field position SF, say to any field-control position between F3 and SF. The purpose of this field-controller contact-segment will be subsequently described.

Responsive to the dropping-out of the transition-switch J (which was deenergized as a result of the energization of the parallel-connection switch M), the back-contact 238 of this transition-switch recloses, and re-initiates the switch-progression of the resistance-shorting contacts S3 to S10, under the control of the switches 3-4 and 9-10, through the circuits which have been previously described. This establishes the maximum armature-voltage conditions on the motors, and it completes the connections for the full-field parallel-connection operation of the traction motors.

As soon as the resistance-shorting switch 9-10 closes, it closes an additional contact 254, which energizes a field-controller actuating-circuit from the progress-wire 41, said circuit extending from the wire 41 through the previously mentioned make-contact 254 of the resistance-shorting switch 9-10, a back-contact 256 of the third progression-switch 3-4, a make-contact 251 of the parallel-connection switch M, and a make-contact 258 of the line-switch LS2, and thence to the short-field wire 39 of the field-controller FC.

The short-field wire 39 of the field-controller FC energizes the short-field coil FC-SF, or other means which may be used to move the field-controller from its full-field position FF to its short-field position SF. This starts the progressive operation of the field-controller, and it may be brought about in any one of several ways. In the illustrated form of embodiment, since the power for the short-field wire 39 is obtained from the progress-wire 41, which is under the control of the limit-relay CR, the field weakening progression of the field-controller FC progresses under the control of the limit-relay CR, until the short-field position SF is reached. This completes the connections for the short-field parallel-connection operation of the traction-motors, thus completing the acceleration-progression.

If, now, the master-controller MC is returned to its off-position, the car or train being now running at some considerable speed, the master-controller will energize the train-line wire 3, which may be described as the brake-wire 3, because it is used to set up the dynamic-braking circuits for the motors during the coasting operation. When the braking-protective relay BP is used, as shown, the brake-wire 3 is also used to directly energize a hold-coil BP-Hold of the braking-protective relay BP, and this hold-coil may be regarded as representative of any holding-means which is effective only after the protective relay BP has previously been moved to its actuated position. When a separate holding-coil, BP-Hold, is used as such a holding-means for the BP relay, said coil will be made so as to be too weak to pick up the BP relay if the relay is in its non-actuated position when the hold-coil is energized, but the hold-coil BP-Hold has enough energy to hold the relay actuated or closed, once it has been actuated.

As set forth in the previously mentioned application of Burkhardt and myself, the BP-Hold coil is also provided with a second energizing-circuit, which is independent of the brake-wire 3, and

thus operative in any of the three on-positions of the master-controller MC. This second hold-coil energizing-circuit includes a make-contact 259 of this brake-protective relay BP, and this make-contact 259 is used to energize the brake-wire 3 from the previously described control-circuit 120, which is under the control of the line-relay LR, so that the control-circuit 120 is energized whenever there is a failure of the line-voltage, at a time when the train-line wire 12' is energized, that is, at a time when the master-controller is on any one of its three on-positions, as previously described. In this way, I not only maintain the energization of the BP-Hold coil under the no-voltage conditions just described, thus making sure that the brake-protective relay BP remains in its actuated condition, but I also immediately energize the brake-line 3, without waiting for the master-controller MC to be returned to its off-position, which establishes the coasting braking-circuit connections, as will now be described.

The brake-wire 3 is connected, through an LS1 back-contact 260 and a BP make-contact 261, to a control-circuit 31B. This control-circuit 31B is connected, through a G1 back-contact 262, to the previously described control-circuit wire 31, which energizes the previously described parallel-motoring switches M and G through the JR back-contact 251 and the control-wire 66. The control-conductor 31B is also connected, through a G1 back-contact 263, to a control-wire 31C, and thence to the positive terminal of the braking-switch coil B1, the negative terminal of which is connected in a circuit which includes a B5 back-contact 265, a conductor 102, another B5 back-contact 266, a conductor 104, and a JR back-contact 267, and thence to the grounded negative battery-terminal (-). The closure of the switches M, G and B1 completes the establishment of a weak coasting-operation dynamic-braking circuit-connection for the traction-motors, with all of the available dynamic-braking resistances R5, R2 and R3 in circuit, this dynamic-braking resistance being large enough so that the braking tractive-effort is usually quite weak, at moderate motor-speeds, thus permitting the train to coast, with little or no sensible or perceptible braking-effect, as long as the field-controller FC remains in its short-field position.

A connection is also provided, for controlling the field-controller FC during the coasting-operation. In accordance with a known practice, I provide a circuit extending from the control-wire 31C, through a back-contact 268 of a brake-relay BR, to a control-circuit 32, and thence through the back-contact 269 of a spotting-relay SR, to the full-field wire 33 of the field-controller FC. The brake-relay BR was shown and described in a Riley-Purifoy Patent 2,523,143, granted September 19, 1950. The spotting relay SR is a previously used relay, having an operating-coil SR which is included in the common brake-circuit connection 198, so that this relay is responsive to the braking-circuit current. This spotting-relay SR is adjusted to have a low-current pickup-value, so that it can hold the braking-circuit current to a small value suitable for spotting purposes, during the coasting operation of the traction-motors, as is well understood in the art.

The full-field wire 33 of the field-controller FC energizes a full-field coil FC-FF, or other means for causing the field controller FC to move or progress from its short-field position SF to its

full-field position FF. This energization of the full-field coil FC—FF under the control of the spotting relay SR thus progressively adjusts the field-controlling means FC toward its full-field position, as spotting-conditions may require.

In accordance with a known control-method, the spotting-relay SR has a make-contact 270 which connects the circuit 32 to a circuit 36, which goes to a field-controller contact-segment 271, which is closed only during certain early points in the progressive movement of the field-controller FC from its full-field position FF toward its short-field position SF. This field-controller segment 271 is preferably opened at a certain point near the short-field-position SF, preferably before the field-controller reaches this short-field position SF. As shown, I prefer to have this field-controller segment 271 closed at the positions FF through F3 of the field-controller FC. This field-controller segment 271 is used to connect the wire 36 to the short-field wire 39 of the field-controller FC. In this way, when the spotting current is too large, that is, large enough to pick up the spotting-relay SR, the spotting current is reduced by adjusting the motor-fields toward a weaker condition, by making the field-controller FC progress in the direction towards its short-field position, but this progression is usually arrested before the field-controller returns all of the way back to its original short-field position SF, which it occupied before the spotting-control commenced to operate.

A service braking-application is made by the closure of the brake-lever 202, which energizes the full-brake wire 5 from the brake-wire 3. This full-brake wire 5 is connected directly to the coil BR of the brake-relay BR. The brake-relay BR has a make-contact 272, which connects the full-brake line 5 to the conductor 45 which leads up to the limit-relay progression-circuit 46, thus putting the braking progression under the control of the back-contact 199 of the limit-relay or current-relay CR, as well as under the control of the BP make-contact 230, both of which are in circuit between the conductor 45 and the limit-relay progression-circuit 46. At the same time, the opening of the back-contact 268 of the now-actuated brake-relay BR takes the braking progression out of the control of the spotting relay SR.

Whenever a braking-application is called for, the energization of the brake-relay BR closes a BR make-contact 273, which is used in the initiation of the dynamic-braking progression. Thus, the BR make-contact 273 is used to make a connection from the limit-relay progression-circuit 46 to the full-field wire 33 of the field-controller FC. This causes a progression of the field-controller FC until it reaches its full-field position FF, under the control of the limit-relay CR.

The closure of the brake-relay BR also closes a make-contact 274 which makes a connection from the control-wire 31C to a braking-operation hold-wire 71, in readiness for use in the subsequent brake-progression operations.

When the braking-controlling progression has proceeded to the point at which full-field conditions are restored in the traction-motors, the field controller FC closes a full-field contact-member 276, which closes a circuit from the full-field wire 33 to a conductor 49, and thence through a BR make-contact 277 to a braking-progression circuit 48.

The energization of the braking-circuit pro-

gression-wire 48 immediately serves, through a B1 make-contact 278, which is already closed, to energize a circuit 72, which is connected, through a B2 back-contact 279, to a circuit 82 which is connected to the positive terminal of the B2 actuating-coil, the negative terminal of which is connected to the previously described conductor 102. The B2 switch thus picks up and closes its main contact B2 which shorts out a part of the 10 braking-resistance R5 in the common dynamic-braking circuit 198 of the traction-motors. The actuation of the B2 switch also closes a make-contact 280 which establishes a holding-circuit for the wire 82 from the hold-wire 71.

15 A circuit is next established from the lower end of the progression-wire 48, through a B6 back-contact 281, to a conductor 75, and thence through a B2 make-contact 282, which has just been closed, to a conductor 85 which is connected to the positive terminal of the B5 actuating-coil, the negative terminal of which is connected to the previously mentioned wire 104. The B5 switch closes its main-circuit contact B5, which shorts out more of the braking-resistance R5 in 20 the common dynamic-braking circuit 198 of the traction-motors. At the same time, the B5 switch closes a make-contact 283 which establishes a holding-circuit from the conductor 85 back to the hold-wire 71.

25 30 The energization of the braking-progression switch B5 opens its previously mentioned back-contacts 285 and 286, thus dropping out the switches B1 and B2, the main contacts of which are both short-circuited, now, by the main contact B5. The dropping-out of the B1 switch closes its lowermost back-contact 284, which completes a circuit from the conductor 75 to a B5 make-contact 285, and thence to a wire 86, which is connected to the positive terminal of 35 the B6 coil, the negative terminal of which is connected to the wire 104. The B6 switch thus closes, and closes its main contact B6 which further shorts out some of the braking-resistor R5, thus still further reducing the effective braking-resistance in the dynamic-braking circuits. At 40 the same time, the actuation of the B6 switch closes its make-contact 286, which establishes a holding-circuit for the wire 86 from the wire 71.

45 50 The actuation of the B6 switch also closes a make-contact 287, which connects the progression-wire 48 to the previously described conductor 72, thereby reenergizing the B2 switch, the negative circuit of which is now completed from the wire 102, through a B6 make-contact 55 288, to the wire 104.

55 60 It will be understood that all of these braking-progression operations are under the control of the limit-relay progression-circuit 46, which interrupts the progression whenever an excessive motor-current causes an opening of the current-relay back-contact 199, which is connected in the energizing circuit for said wire 46, thus interrupting the progression until the motor-current subsides to a desirable value.

65 70 The braking-circuit progression-wire 48 is also connected, through a G1 out-contact or back-contact 289, to the accelerating-resistance progression-wire 47.

75 After the second closure or actuation of the B2 switch, so that the B2 and B6 switches are now both closed, a circuit is made, from the accelerating-resistance progression-wire 47, through a B2 make-contact 290 and a B6 make-contact 281, to the previously described conductor 50, thus re-initiating the progression of

the switches 1—2, 3—4, and 9—10, which progressively close the accelerating-resistor switches S1 to S10, thereby cutting out the accelerating resistors R2 and R3 which are in the individual portions of the respective dynamic-braking circuits of the traction-motors, this progression being also under the same limit-relay control.

Ever since the actuation of the B5 switch, a B5 make-contact 202 has been energizing the accelerating-resistance hold-circuit 67 from the braking-operation hold-wire 71, in readiness for this progression of the accelerating-resistor switches S1 to S10. The braking-progression thus continues until substantially all of the braking-resistance is removed from the dynamic-braking circuit, thus resulting in the completion of the dynamic-braking operation, during which the speed of the car or train has been reduced from the initial speed at which the dynamic brake was applied, down to a low speed at which the dynamic brake fades out.

If a braking-operation is to be discontinued, after once having been started, the braking-circuit switches are released by an opening of the brake-handle 202, without requiring the establishment of a (perhaps momentary) power-circuit (or MC on-position), in order to deenergize the braking hold-wire 71. This is accomplished by the BR-contact 274, which is in series with the hold-wire 71. The opening of the brake-handle 202 deenergizes the brake-relay BR and opens its contact 274, without requiring an on-position of the master controller MC to release the brake-wire 3, in order to deenergize the conductor 31C and hence the hold-wire 71.

It has long been customary to automatically adjust the calibration or setting of the limit-relay CR, in order to cause this relay to drop out in response to various accurately controlled desirable minimum motor-current values, during both the acceleration-progression and the dynamic-braking progression. This is conveniently done by various controls for the energization of the rate-coil RC of the limit-relay CR. In the drawing, I have shown two known circuits for the rate-coil control or calibration. One such rate-coil circuit involves the weight-responsive rheostat 200, and is traceable from the positive control-power line (+) through an LS2 make-contact 293, the aforesaid weight-responsive rheostat 200, a resistance 234, a conductor 92, a resistance 295, and the rate-coil wire 95. A second old or known rate-coil energizing-circuit involves the braking-responsive resistance 201, and is traceable from the positive bus (+) through a BR make-contact 296, and the aforesaid braking-responsive rheostat 201 to the conductor 92.

As described in the companion-application of Barclay and myself, I provide my field-controlling means FC with a contact-segment 306 which is closed at all controller-positions except those positions which are close to the full-field position FF. As illustrated, the contact-segment 306 of the field-controller FC is closed in the controller-positions between the intermediate position F3 and the short-field position SF, inclusive. This FC contact-segment 306 is used to make a connection from the train-line wire 6, which controls the switching-operation of the traction-motors, to the train-line wire 4, which controls the progressive series-motor running-connections.

The operation of the simplified illustrated apparatus will be clear from the running comments

which have been made during the progress of the description, as well as from the prior art. A few words of added explanation, as to the features which are more particularly related to my novel control-circuit parts, may, however, be helpful.

In accordance with my present invention, I have in effect nullified the switching-connection and the series-motor connection of the traction motors, whenever the shunted-field connections are established. In this way, I prevent the rough-brake conditions which have sometimes been encountered as a result of the motorman's misuse of his master-controller MC. Sometimes, when the car or train is running at high speed, with the motors in their short-field condition, that is, with the field-controller FC in its short-field position SF, the motorman momentarily throws off the power, establishing a momentary coasting-operation, by moving his master controller MC to the off-position, and then immediately again moves the master controller MC to its switching-position, or No. 1 position, which is not a running-position, and not intended to be used except for slow-speed operations while the car or train is being switched from track to track.

Nevertheless, motormen sometimes leave the master-controller MC in this switching-position while the car or train is running at a high speed, and while the motorman is making up his mind whether he wants to resume full running conditions, with a full-power application, or whether he is going to have to initiate a dynamic-braking operation. Meanwhile, in previous motor-control systems, the traction-motors are connected across the power-supply line in their series motor-connections, and the motor-fields are very weak.

If, now, the motorman should go into a dynamic-braking operation, with the motor-fields in an excessively weakened condition for that particular motor-speed, then the dynamic-braking operation would start with the motors having a very low field-flux. This low-flux condition would be doubly aggravated, not only on account of the presence of the field-shunts X1—RS1 and X2—RS2, which divert a considerable part of what little motor-current there has been, immediately prior to the establishment of the dynamic-braking connections, but the motorizing-currents themselves had been excessively small, because the motorman had been erroneously operating, at a high speed, on his No. 1 switching-position, which means that all of the accelerating-resistances R1, R2, R3 and R4 had been in the motor-circuits, so that very little motor-current could be flowing, that is, prior to our introduction of the new field-controller contact-segment 306.

Thus, when dynamic-braking connections are established, while the motor-flux was so extremely weak, and remembering that the motors have a rather slow time-constant, so that their motor-flux cannot be built up anything like as rapidly as the progression-rate during the build-up of dynamic-braking conditions, then the dynamic-braking currents will at first be extremely low, causing the dynamic-braking progression to proceed at its maximum rate, without interruption by the picking-up of the limit relay CR, so that, when the motor-flux finally builds up to its increased value, too much resistance will have been cut out of the dynamic-braking circuits, and excessive dynamic-braking currents will be obtained.

I avoid these difficulties by, in effect, preventing the motorman from operating a fast-moving car or train with the traction-motors connected in either their switching-connections or their series-motor-connections. Whenever the acceleration-progression of the traction-motor control has advanced far enough to cause the field-controller FC to adjust itself to any of its positions F3 to SF, if the motorman should then move his master-controller MC to its off-position, and should then immediately notch it up again to its No. 1 switching-position, while the train is still running fast, the field-controller contact 306 will connect the switching-controlling wire 6 to the wire 4, and my new field-controller contact 253 will continue this connection on, to the parallel-motor control-wire 66, through the circuit 6-215-60-253-66. At the same time, my new field-controller contact 220 prevents the energization of the series-motor-connection switch JR from the circuit 6-215-60-216-62-220-63.

Consequently, neither the series-motor switching-connections nor the series-motor running-connections are made, under these conditions, by the No. 1 switching-position of the master-controller MC; and the switching-connection train-line wire 4 is connected straight on, to the parallel-connection wire 66, which energizes the parallel-connection switches M and G, which establish the parallel motor-connections. The second line-switch LS2 is picked up through the circuit 4-224-40-225-42, and this switch LS2 thereupon closes its contact 228 and thus energizes the progression-controlling circuit 4-224-40-228-45-199-230-46-231-47. The progress-wire 47 rapidly and uninterruptedly cuts out all motor-resistance during these high-speed parallel-motor-connection operating-conditions, thus materially increasing the field-strength of the motors, even though the motorman should improperly leave his master-controller on its No. 1 switching-position while the car or train is operating so fast.

An advantage of establishing a parallel-motor connection of the traction-motors, with all of the accelerating resistance cut out, instead of permitting the motorman to operate the train on the series-motor connection, with the accelerating-resistance either in or out, while the train is running at speeds high enough to have caused the field-controller FC to have adjusted itself to a shortened-field position, is that the parallel-motor connection causes the motors to draw enough current to build up the field-flux to a reasonably high value. Thus, if the motorman goes into dynamic braking from this operating-condition, the motor-field is reasonably high, and this permits the recapturing of a higher residual voltage, when dynamic brake is applied, than was the case in previous control-systems. The dynamic-braking operation therefore starts out with higher voltages generated in the traction-motors, so that the recalibrated limit relay CR does not immediately cut out too much braking-circuit resistance in an effort to bring up the braking-current to its normal braking value, for which the limit relay is set. Heretofore, considerable overshooting of the control was encountered, resulting in an excessive motor-voltage and excessive motor-current during the first second or so of the dynamic-braking operation. According to my invention, the motor-voltage and the motor-current are started off, at values near the optimum values, when dynamic braking is applied during high-speed operation

of the motor, and this results in protection against motor-flashing and rough brake-buildup.

While I have described my invention in connection with a motorman's manipulation of the master controller after he has attained high-speed operating conditions, the same advantages hold true in regard to the protection of the motors in passing third-rail gaps.

It will be understood, of course, that if the motorman had left his master-controller in the off-position, for even a very brief moment, before going into dynamic braking, the coasting or "spotting" conditions would have been established, wherein the motors would be connected in parallel, and the motor field-strengths would have been properly maintained and adjusted by the mild dynamic-braking currents which flow during coasting or spotting. The trouble came, in previous motor-control systems, when the motorman went into the maximum-resistance series-motor switching-connection while the car was running fast, and then immediately changed into the dynamic-braking connection for a brake-operation.

While I have described my invention, and explained its manner of operation, in connection with a particular simplified illustrative form of embodiment, I wish it to be understood that the efficacy of the invention would not be affected by the addition of desired additional features or safeguards or by the omission of undesired or unnecessary features, or by the substitution of equivalent or alternative forms of various means or elements for performing the essential element-functions which have been described and explained.

I claim as my invention:

1. A motor-controlling assembly, including the combination, with a plurality of series motors to be controlled, each series motor including a motor-armature and a series field winding connected in series therewith, of: (a) an accelerating-controller, having an off-position and a plurality of on-positions, said on-positions including a series-motor-connection running-position, and a parallel-motor-connection running-position; (b) a series-connection control-means, for establishing a power-circuit for energizing the series motors in a series-motor connection in response to the series-motor-connection running-position of said accelerating-controller; (c) a parallel-connection control-means, for establishing a power-circuit for energizing the series motors in a parallel-motor connection in response to the parallel-motor-connection running-position of said accelerating-controller; (d) a variable field-controlling means, for progressively adjusting said series field winding toward a full-field condition and toward a short-field condition, respectively; (e) a progressively operating acceleration-controlling means, for controlling the acceleration of the series-motor means during each of the power-circuit operating-conditions, said acceleration-controlling means including a first-operating voltage-controlling means for controlling the voltage which is effective on the motor-armature, and a finally operating field-controlling means for causing said field-controlling means to progressively adjust said series field winding toward its short-field condition in the parallel-motor power-circuit connection; and (f) a shortened-field-responsive means, responsive to a shortened-field condition of said field-controlling means, and responsive to all of the on-positions of the accel-

erating-controller, for establishing the parallel-motor power-circuit connection and nullifying all accelerating-controller on-positions other than the parallel-motor-connection running-position.

2. A motor-controlling assembly, including the combination, with a plurality of series motors to be controlled, each series motor including a motor-armature and a series field winding connected in series therewith; of: (a) a supply-circuit for the series motors; (b) a power-switch means, for establishing a power-circuit for energizing the series motors, first in a series-motor connection, and then in a parallel-motor connection, from the supply-circuit; (c) a braking-switch means, for establishing a dynamic-braking circuit for the series motors; (d) a variable field-controlling means, for progressively adjusting said series field winding toward a full-field condition and toward a short-field condition, respectively; (e) a progressively operating acceleration-controlling means, for controlling the acceleration of the series-motor means during each of the power-circuit operating-conditions, said acceleration-controlling means including a first-operating voltage-controlling means for controlling the voltage which is effective on the motor-armatures, and a finally-operating field-controlling means for causing said field-controlling means to progressively adjust said series field winding toward its short-field condition in the parallel-motor power-circuit connection; (f) a progressively operating spotting-controlling means for controlling the spotting-adjustment of the dynamic-braking circuit during coasting conditions, said spotting-controlling means including a means for causing said field-controlling means to progressively adjust said series field winding toward its full-field condition; (g) a progressively operating braking-controlling means, for controlling the braking-adjustment of the dynamic-braking circuit during dynamic-braking conditions, said braking-controlling means including a first-operating means for causing said field-controlling means to adjust said series field winding to its full-field condition; (h) an accelerating-controller, having an off-position, a switching-position, a series-

motor-connection running-position, and a parallel-motor-connection running-position; (i) a braking-controller, having an off-position and an on-position or positions; (j) a starting-circuit means, for closing the power-switch means in a series-motor connection, while maintaining said progressively operating acceleration-controlling means in its lowest-speed condition, in response to a switching-position of the accelerating-controller; (k) an accelerating-circuit means, responsive to a closed condition of the power-switch means, and each of the running-positions of the accelerating-controller, for causing a progressing operation of the progressively operating acceleration-controlling means; (l) a spotting-circuit means, responsive to an off-position of the accelerating-controller and an off-position of the braking-controller, for closing the braking-switch means and causing a progressing operation of the spotting-controlling means; (m) a braking-circuit means, responsive to an off-position of the accelerating-controller and an on-position or positions of the braking-controller, for causing said field-controlling means to adjust said series field winding toward a fuller field; and a means, operative after full-field conditions have been established during dynamic-braking conditions, for causing a continuing progressive operation of the progressively operating braking-controlling means; and (n) a means, responsive to a shortened-field condition of said field-controlling means, for establishing a temporary circuit-connection between the switching-position and the parallel-motor-connection running-position of the accelerating-controller.

3. The invention as defined in claim 2, characterized by said shortened-field-responsive temporary-circuit connection-means (n) including an accelerating-circuit means for causing a progressive operation of the first-operating means of said acceleration-controlling means (e).
